UNITED STATES PATENT OFFICE.

ROY X. TUTTLE, OF BATTLE CREEK, MICHIGAN, ASSIGNOR TO SANITARIUM & HOSPITAL EQUIPMENT COMPANY, OF BATTLE CREEK, MICHIGAN.

THERAPEUTIC LAMP.

Application filed November 27, 1926. Serial No. 151,158.

The main object of this invention is to provide an improved therapeutic lamp for use in bath cabinets and the like which is highly efficient in the production of intra red rays.

A further object is to provide a lamp or therapeutic unit of the class described which may be used without liability of injury to the patient or the operator.

Objects pertaining to details and economies of my invention will definitely appear from the detailed description to follow. The invention is clearly defined and pointed out in the claims.

A structure embodying the features of my invention is clearly illustrated in the accompanying drawing forming a part of this application, in which:

Fig. 1 is a fragmentary side elevation of a lamp or unit embodying the features of my invention.

Fig. 2 is a fragmentary view partially in section on a line corresponding to line 2—2 of Fig. 3.

Fig. 3 is a horizontal section on a line corresponding to line 3—3 of Fig. 2.

Referring to the drawing, my improved therapeutic lamp unit comprises a base 1 having a central opening 2 therein shouldered at 3 to form a seat for the socket plug 4 which, in the embodiment illustrated, is adapted to fit or coact with the common form of lamp socket.

The resistance wire 5 is mounted upon the core 6 which has a spiral groove to receive the wire, thereby keeping the coils thereof properly separated. This core is preferably formed of lava. Around this core is a lava tube 7 which is of such dimensions that it is spaced from but its inner side lies adjacent to the resistance wire and core so that the tube is heated from the resistance element. The lower end of the tube is seated in the opening 2 in the base upon the plug 4.

A yoke-like frame 8 is mounted on the base and carries a screw 9 which clamps the cap 10 upon the end of the tube, this cap being recessed to receive the end of the tube. The parts are thus maintained in fixed relation when assembled and at the same time permit easy assembling and disassembling. This cap 10 is also preferably of lava.

The cylindrically curved segmental reflector 11 is of black iron which reflects only

the so-called dark rays. A foraminated guard or screen 12 closes the front of the lamp so that the operator or patient does not come in contact with the heated parts. The reflector and this screen are arranged to embrace the periphery of the base and are clamped thereon by means of the frame 8, screws 13 being arranged through the frame and the superimposed or overlapping edges of the reflector and screen as shown in Figs. 2 and 3. The frame 8 serves as a support for the reflector and screen.

My improved lamp or therapeutic device is especially designed by me for use in bath cabinets and treatments where intra red rays are desired and I have illustrated and described my improvements as I have embodied the same for that purpose. I have not attempted to illustrate or describe certain modifications or adaptations which I contemplate as I believe this disclosure will enable the adaptations or embodiment of the invention as may be desired.

Having thus described my invention what I claim as new and desire to secure by Letter's Patent is:

1. In a device of the class described, the combination of a base having a central shouldered opening therein, a yoke-like frame carried by said base, a socket plug seated on the shoulder in said opening of said base, a core on said plug having a resistance coil thereon, a tube disposed over said core with its lower end within said base opening and seated on said socket plug, a cap of lava recessed to receive the upper edge of said tube, a screw threaded into said frame to engage said cap, a cylindrically curved segmental reflector mounted to embrace the edge of said base, and a segmental curved foraminated guard mounted to embrace the opposite side of said base, the edges of said reflector and guard being overlapped within and clamped to said base by said frame, said frame constituting a support for said reflector and guard.

2. In a device of the class described, the combination of a base having a central shouldered opening therein, a yoke-like frame carried by said base, a socket plug seated on the shoulder in said opening of said base, a core on said plug having a resistance coil thereon, a tube disposed over said core with its lower end within said base opening and seated on said socket plug, a

- cap of lava recessed to receive the upper edge of said tube, and a screw threaded into said frame to engage said cap.
3. In a therapeutic device, the combination of a base having an opening therein, a socket plug seated in said opening, a heating element comprising a core having a resistance coil thereon on said plug, a tube embracing said core and disposed in close proximity to but spaced from the said heating element, a yoke-like frame on said base member, a cap recessed to receive the upper end of said tube, and a screw threaded through said frame to engage said cap.
4. In a therapeutic device, the combination of a base, a frame carried by said base, a core of lava carrying a resistance element, a tubular radiating element embracing said core, a cylindrically curved segmental reflector of black metal mounted on said base, and a segmental curved foraminated guard mounted on the opposite side of said base, the edges of said reflector and guard being overlapped within and clamped to said base by said frame, said frame constituting a support for said reflector and guard.
5. In a therapeutic device, the combination of a base, a core of lava carrying a resistance element, a tubular radiating element embracing said core, a cylindrically curved segmental reflector of black metal mounted
- on said base, and a segmental curved foraminated guard mounted on the opposite side of said base.
6. In a therapeutic device the combination of a base, a heating element comprising a core of lava having a resistance thereon, a tubular radiating element embracing said core and disposed in close proximity to but spaced from the said heating element, a yoke-like frame on said base member, a cap recessed to receive the upper end of said radiating element, and a screw threaded through said frame to engage said cap.
7. In a structure of the class described, the combination of a base, a heating element mounted thereon and comprising a core having a resistance element thereon, a tube of earthy material embracing said core to be heated by said resistance element, and a cylindrically curved reflector of black metal.
8. A structure of the class described comprising a socket plug, a heating element thereon comprising a core, a coil of resistance wire on said core, and a tube of lava embracing said core with its wall in close proximity to but spaced from said core whereby the tube is heated from said heating element.

In witness whereof I have hereunto set my hand.

ROY X. TUTTLE.
